(57) **CLAIM**

The ornamental design for an electronic device as shown
and described.

DESCRIPTION

FIG. 1 is a top, front, and side isometric view of a first
embodiment of an electronic device embodying the new
design;

FIG. 2 is a bottom, back, and side isometric view thereof;
FIG. 3 is a top view thereof;

FIG. 4 is a bottom view thereof;

FIG. 5 is a first side view thereof;

FIG. 6 is a second side view thereof;

FIG. 7 is a back view thereof;

FIG. 8 is a front view thereof;

FIG. 9 is a cross-sectional view along lines 9-9 in FIG. 3;
and

FIG. 10 is a detail view of area 10 in FIG. 9.

FIG. 11 is a top, front, and side isometric view of a second
embodiment of an electronic device embodying the new
design;

FIG. 12 is a bottom, back, and side isometric view thereof;
FIG. 13 is a top view thereof;

FIG. 14 is a bottom view thereof;

FIG. 15 is a first side view thereof;

FIG. 16 is a second side view thereof;

FIG. 17 is a back view thereof;

FIG. 18 is a front view thereof;

FIG. 19 is a cross-sectional view along lines 19-19 in FIG.
13; and

FIG. 20 is a detail view of area 20 in FIG. 19.

The broken lines showing portions of the electronic device
throughout the figures, as well as those indicating cross-
sectional and enlarged views, form no part of the claimed
design. Also, the dash-dot broken lines depicted on interior
